UNITED STATES PATENT OFFICE.

HUGH G. BUCHAN, OF ST. LOUIS, MISSOURI, ASSIGNOR TO BUCHAN TELEPHONE RECORDS COMPANY, OF ST. LOUIS, MISSOURI, A CORPORATION OF DELAWARE.

CLAMPING MEMBER FOR LOOSE-LEAF BINDERS.

Application filed May 10, 1926. Serial No. 107,897.

This invention relates to clamping members for loose leaf binders.

It is among the objects of this invention to produce an economical clamping member 5 from sheet metal which eliminates the usual integral hinge eyelets providing a structure which can be completely sheathed and encompassed by hinge members which serve to hold the ends of the clamping member in juxtaposition.

The invention comprises the novel structure and combinations hereinafter described and more particularly pointed out and defined in the appended claims.

15 In the accompanying drawings which illustrate certain preferred embodiments of this invention and in which similar reference numerals refer to similar features in the different views:

20 Figure 1 is a top plan view of a binder embodying this invention.

Figure 2 is an enlarged plan view of the clamping member with fragments of the cover attached thereto.

25 Figure 3 is an enlarged sectional view upon the line 3—3 of Figure 2.

Figure 4 is a longitudinal sectional view through the clamping member.

30 Figure 5 is a sectional view upon the line 5—5 of Figure 4.

Figure 6 is a plan view of a slightly modified form of the invention.

35 Figure 7 is a top plan view of the modified form of clamp showing fragments of the cover.

Figure 8 is an end elevational view of the clamping member.

Figure 9 is a longitudinal sectional view through the clamping member.

40 Figure 10 is an enlarged sectional view upon the line 10—10 of Figure 9.

Figure 11 is a sectional view through a further modified clamping member.

In referring to the drawings in Figures 1 45 to 10 it will be observed that each clamping member consists of a tube of sheet metal 1 which may be elliptical or oblong in cross section. It is made by rolling or forming a rectangular sheet of metal into proper cross sectional form and bringing the edges of such sheet into juxtaposition for forming the inner edge of the clamping member. A pair of straw board sleeves 2 or the like telescope over each tube. These sleeves are suitably

spaced apart at their adjacent ends for receiving a central strap or loop of metal 3 and their outer ends are spaced inwardly of the ends of the metal tubes to allow space for end loops 3 or 3^a. A fabric sheath 4 completely encloses each tubular clamping member and extends over the straw board sleeves 2. The metal loops 3 extend beyond the inner edge of each clamping member to receive apertured bearing blocks 5 which embrace the inner side of each clamping member and which are preferably convex upon their inner portions. The loops 3^a which are end loops and differ from the loops 3 in that they have a wall 3^b upon their outer side to close the ends of the clamping member, likewise extend beyond the inner edge of the clamping member for receiving apertured bearing blocks 5^a which embrace the inner edge of the clamping member. The straps or loops 3 and 3^a in combination with the bearing blocks compress the fabric sheath 4 tightly around the metal sheath and against the ends of the straw board sleeves 2.

In Figures 1 to 5, the illustrated structure comprises end plugs 6 which act as closures for the ends of the clamping member. These end plugs have inwardly extending apertured projections 6^a, the apertures of which are in alinement with the apertures in the blocks 5. The apertures of the blocks 5^a and 5 shown in Figure 9, are also in alinement. A cover 8 is adapted to be attached to each clamping member by a suitable hinge rod extending through the apertures of the bearing blocks. The end caps 3 and plugs 6 may be retained in position by suitable screws 9 extending therethrough and also through the metal tube 1. The end members 3^a may be held in position in a similar way or by stamping tangs 10 therefrom into the fabric sheath.

In Figure 11, I have shown a modified form of clamping member. Instead of using a hollow tubular member, a flat rectangular solid clamping member 11 may be used and rectangular loops of metal 12 may surround the same and extend beyond the inner edge thereof for receiving an apertured bearing block 13 that forms the hinge connection for the cover.

I am aware that many changes may be made, and numerous details of construction may be varied through a wide range without departing from the principles of this invention.

tion, and I therefore do not purpose limiting the patent granted hereon, otherwise than necessitated by the prior art.

I claim as my invention:

5. 1. A clamping member for a loose leaf binder having metal loops surrounding the same and extending therebeyond at one edge and apertured hinge blocks positioned between the extended ends of said loops and said 10 clamping member.

2. In a clamping member for loose leaf binders, a tubular member, a covering there-around, and straps embracing said member and sunk into said covering for holding the 15 same therearound.

3. In a clamping member for loose leaf binders, a tubular member, spaced sleeves on said member, straps around said member between said sleeves and adjacent the outer ends 20 thereof, said straps extending beyond one edge of said clamping member and apertured bearing blocks in the extended ends of said straps.

4. A clamping member for loose leaf binders comprising a hollow metal member, 25 spaced sleeves upon said member, a fabric sheath covering said sleeve and member, metal loops surrounding said member at the ends of said sleeves, and means carried by said loops for hinging the cover of the binder thereto.

30 5. In a clamping member for loose leaf

binders, a flattened hollow metallic clamping member, a metallic loop surrounding an intermediate portion of said member, metallic loops surrounding the end portions of said member and provided with means for closing 35 said ends, and apertured bearing blocks positioned within said loops adjacent one edge of said clamping member for hinging a cover member for the binder thereto.

6. In a clamping member for loose leaf 40 binders, a flattened tubular member, spaced sleeves on said member, a covering for said sleeves and member, spaced metal loops surrounding said member and clamping the covering thereon, and apertured bearing blocks 45 positioned within said loops adjacent one edge of said clamping member.

7. In a clamping member for loose leaf binders, a flattened hollow member, sleeves thereon, a covering inclosing said sleeves and 50 member, metal loops surrounding said covering, said loops extending beyond one edge of said member, apertured bearing blocks confined in the extended portions of said loops, said blocks being adapted for hingedly supporting a cover member of the binder. 55

In testimony whereof I have hereunto subscribed my name.

HUGH G. BUCHAN.
